UNITED STATES PATENT OFFICE.

HARRY J. MOREY, OF SYRACUSE, NEW YORK.

ELECTRICAL FIXTURE.

Application filed March 22, 1920. Serial No. 367,806.

To all whom it may concern:

Be it known that I, HARRY J. MOREY, a citizen of the United States, and residing at Syracuse, Onondaga County, State of New York, have invented certain new and useful Improvements in Electrical Fixtures, of which the following is a specification.

The object of the present invention is to provide means for conveniently connecting an electrical receptacle with the line wires in an outlet box. The invention comprises as insulating base which serves as a cover to the outlet box and a support for the receptacle and within which the line terminals and lead terminals are located for convenient access through an opening in the front of the base. It also comprises means for attaching the base to the outlet box, and means for securing a receptacle in the front opening in the base to close the opening, and various other improvements in details, all of which will be described in connection with the accompanying drawings in which

Figure 1 is a side elevation, partly in section of one embodiment of the invention, the parts being separated to better illustrate their construction;

Figure 2 is a similar view showing the same parts assembled;

Figure 3 is a front view of the base shown in Figures 1 and 2 with part broken away and the transverse member partly in section;

Figure 4 is a rear view of the base shown in Figures 1, 2 and 3;

Figure 5 is a plan view of the bridge plate;

Figure 6 is a sectional view of an embodiment of another form of the invention;

Figure 7 shows the base of Figure 6 in section with receptacle attached, and

Figure 8 is a partial front view of the base of Figures 6 and 7.

Referring to Figures 1 to 5 of the drawings, 10 indicates an outlet box of usual construction, 11 conduits connected to the box and 12 line wires extending through the box and conduits.

An insulating base 13 is suitably formed to fit over and cover the outlet box and to receive a receptacle. The base is preferably provided with an integral transverse member 14 having lateral projections 15 at its middle part carrying line terminals 16. A bridge plate or bar 17 is connected to the front of the outlet box by means of screws passing through slots in the bar and the

insulating base is connected to the bridge plate, as shown, by a central screw 18. In assembling the parts the transverse member 14 of the base rests on the bridge plate 17, thus leaving a large opening on each side of the bridge plate and the transverse member through which the line wires may be drawn to engage them with the line terminals 16. The bottom of the transverse member 14, as shown in Figures 2 and 4, is preferably formed with a rib 14a which fits between flanges 17a of the bridge plate, thus making it convenient to accurately locate the base on the bridge plate and outlet box.

The insulating base is provided with an opening on its front side to receive a receptacle and with means for connecting the receptacle to the base. As shown in Figures 1, 2 and 3 a perforated ring 19 is attached to the base by lugs 20 and suitable screws and the receptacle 21 is provided with tongues or projections to engage the perforations in the ring 20 in a well known manner. The receptacle may be of any desired character, such as a lamp socket, and it is connected by short lead wires 22 with binding screws 23 connected with the line terminal plates 16.

In assembling the electrical fixture described the insulation is removed from short sections of the line wires as shown in Figure 1 and the bridge plate and insulating base are then connected to the outlet box as described. The line wires are then pulled down and engaged with the line terminals 16 by any suitable instrument inserted through the opening in the front of the base which receives the receptacle. The short lead wires or branch wires 22 are then connected with the binding screws 23 and with the base of the receptacle in the manner shown in Figure 1 and the receptacle is then connected with the locking ring 19 in the usual manner as shown in Figure 2.

It will be obvious that the electrical fixture described contains a minimum of parts and can be wired with great ease and without cutting the line wires or requiring any soldered connections.

In that form of the invention shown in Figures 6, 7 and 8 the base 30 is provided with openings 31 to receive screws 32 by means of which the base may be connected directly to the outlet box 10. The base is provided with an opening in front for the

attachment of a receptacle 33 which as shown is provided with a porcelain shell. The base is also provided with a transverse member 34 at the rear having lateral projections 35 which carry line terminals 36. The line wires are engaged with these terminals by inserting a suitable instrument through the base into the outlet box and pulling the wires down and securing them as clearly 10 shown in the drawings.

Instead of using branch wires to connect the receptacle with the line wires as shown in Figures 1 and 2, one of the line terminals 36 has a forward extension carrying a side 15 contact 37 against which the side contact on the receptacle 33 abuts when the parts are assembled, and the other line terminal 36 carries a centrally arranged bracket 38 to which the center contact of the receptacle is 20 connected by a screw 39 which screw serves to hold the receptacle in place on the base and may also serve as the center contact of the lamp socket or receptacle.

Having described the invention what is 25 claimed is:

1. An insulating base for an electrical fixture comprising, an insulating body having an opening from front to rear, and an integral member within and bridging said 30 opening provided with line terminals, branch terminals and means for securing the base to a supporting member, said terminals and said means being accessible through said opening from the front and said base having means whereby a receptacle may be 35 attached to close the front of said opening.

2. The combination with an outlet box of a bridge plate attachable to the front of said box, an insulating base adapted to fit the 40 front of the box and having a central opening to receive a receptacle, and means for attaching the base to said bridge plate at its central portion, said means being accessible through said central opening.

3. The combination with an outlet box, of a transverse bridge plate secured to and arranged across the front of the box, said plate leaving openings through which access may be had to the line wires, an insulating base 50 in front of said box and bridge plate, and means for centrally attaching said base to said bridge plate, said base having an opening therethrough so formed as to furnish access to the line wires and to the attaching means.

4. The combination with an outlet box, of a transverse bridge plate arranged across the front of the box, leaving openings through which access to the line wires may be had, an insulating base in front of said box and bridge plate, said base having an integral transverse member having line terminals secured thereon, and also having a central aperture through which said transverse member and line terminals may be

reached, and means accessible through said central aperture for attaching said transverse member to said bridge plate.

5. The combination with an outlet box, of a transverse bridge plate arranged across the front of the box, an insulating base in front of said box and bridge plate having a central opening and an integral transverse member with lateral projections and line terminals on said lateral projections, said transverse member also having a central aperture therein, and means insertable through the central aperture in the transverse member to engage the bridge plate, whereby the base may be secured to the bridge plate, the line terminals and said securing means being accessible through the opening in the base. 70 75 80

6. An electrical fixture comprising an outlet box, an insulating base fitting and closing the front of said box having an opening therethrough from front to rear, the structure and form of the base around and forming the front end of the opening being such as to adapt it to receive and be closed by a receptacle, line terminals in said opening between its ends and accessible from the front of the base and cooperating means on said box and the rear portion of said base within the opening for securing the base to the box embodying a movable connecting part within the straight line margins of said front opening whereby the means for securing the base to the box may be operated by an implement passing through the front opening. 90 95 100

7. An electrical fixture comprising an outlet box, an insulating base having one end fitting and closing the front of the box and extending outwardly therefrom and having a transverse member between the ends of the base across the front of the box and an opening in the outer end in line with said transverse member, line terminals on said transverse member, and means for clamping the line wires to said terminals with operating means facing and operatively accessible through said opening in the outer end. 105 110 115

8. An electrical fixture comprising an outlet box a bridge plate extending across the open front of the box and secured thereto at its ends, an insulating base having one end fitting and closing the front of the box and extending outwardly therefrom and having a transverse member between the ends of the base across the front of the box fitting said bridge plate and an opening in the outer end in line with said transverse member, line terminals on said transverse member, and means for clamping the line wires to said terminals with operating means facing and operatively accessible through said opening in the outer end, means operatively accessible through said opening for securing said transverse member to said bridge plate at its central portion. 120 125 130

9. An electrical fixture comprising a one-piece base of insulating material having at one end surfaces near the margin adapted to make contact with and fit the outer surfaces 5 of a support containing line wires around an outlet opening in said support thus serving as a closure, so formed interiorly as to have a pair of spaced openings entering on the side adapted to fit the support within the 10 contact margins, forming between them a transverse member with side projections adapted to receive line terminals, said side openings joining each other beyond said transverse member forming a single opening 15 at the side opposite the contact surfaces, the said projections being within the marginal lines of otherwise open diverging passageways through the base from the single opening on one side to the two openings on the 20 other side.
10. An electrical fixture comprising a one-piece base of insulating material having at one end surfaces near the margin adapted to make contact with and fit the outer surfaces 25 of a support containing line wires around an outlet opening in said support thus serving as a closure, so formed interiorly as to have a pair of spaced openings entering on the side adapted to fit the support within 30 the contact margins, forming between them a transverse member having portions on opposite sides so constructed as to receive and carry line terminals between its ends, said side openings joining each other beyond said 35 transverse member thus forming a single opening in the side of the base opposite the contact surfaces forming diverging passageways through the base from the single opening in one face to the two side openings in the other face with the portions of the transverse member adapted to receive and carry the line terminals within their marginal lines.
11. An electrical fixture comprising an insulating base adapted to serve as a closure 40 for an outlet box having end surfaces at the margins adapted to fit the side edges of said box around its open end and having an integral transverse member with lateral projections 45 on opposite sides therein near the plane of contact with the box providing side openings, the said base having an opening to receive a receptacle at the end opposite to that having the marginal contact surfaces, in open communication on straight 55 lines from its outer end to and through said side openings and to said transverse member and its lateral projections.
12. An electrical fixture comprising a base 60 composed of insulating material having end surfaces at its edges adapted to fit against the outer surfaces of a support for enclosing line wires around an outlet opening in said support serving as a closure, the said 65 base embodying a surrounding wall extend- ing from said edge surfaces on the general lines of a cone with a central opening at its end and an integral transverse member within said base with its outer surface in a plane substantially parallel to and near the 70 plane of said end surfaces and its inner surface spaced therefrom a distance materially less than the length of the base thus forming passageways through said base from the opening in its smaller end by said transverse member into said support for line wires. 75
13. An electrical fixture comprising a base composed of insulating material having end surfaces at its edges adapted to fit against the outer surfaces of a support for enclosing line wires around an outlet opening in said support serving as a closure, the said base embodying a surrounding wall extending from said edge surfaces on the general lines 80 of a cone with a central opening at its end and an integral transverse member within said base with its outer surface in a plane substantially parallel to and near the plane of said end surfaces and its inner surface spaced therefrom a distance materially less than the length of the base thus forming passageways through said base from the opening in its smaller end by said transverse member into said support for line wires, line 85 terminals on said transverse member and means for clamping line wires to said terminals operatively accessible through said central end opening. 90
14. An electrical fixture comprising a base composed of insulating material having end surfaces at its edges adapted to fit against the outer surfaces of a support for enclosing line wires around an outlet opening in said support and serving as a closure therefor, 100 the said base being so formed interiorly as to have two openings entering the end adapted to fit the support with their outer walls tapering inwardly to a point near the opposite end of the base, and a single opening 110 entering the base at said opposite end midway between said first mentioned openings and extending inwardly a material distance entering and joining said first mentioned openings at its sides said openings being 115 formed by a transverse binding screw carrying member across the inner end of said last mentioned opening and between said first mentioned openings. 120
15. An electrical fixture comprising a base composed of insulating material having end surfaces at its edges adapted to fit against the outer surfaces of a support for enclosing line wires around an outlet opening in said support serving as a closure, the said base being so formed interiorly as to have two 125 openings entering the end adapted to fit the support with their outer walls tapering inwardly to a point near the opposite end of the base, and a single opening adapted to

receive a receptacle entering the base at said opposite end midway between said first mentioned openings and extending inwardly a material distance, joining said first mentioned openings, said openings being formed by a transverse member across the inner end of said last mentioned opening at the end fitting the support between said first men-

tioned openings, line terminals on said transverse member and means for clamping 10 line wires to said terminals accessible for operation by a hand tool through said single opening.

In testimony whereof I affix my signature.

HARRY J. MOREY.
